his Atty.

UNITED STATES PATENT OFFICE.

OLIVER COLBORNE, OF CHICAGO, ILLINOIS, ASSIGNOR TO THE TOMLINSON VENEER BARREL COMPANY, OF INDIANAPOLIS, INDIANA.

VENEER-PACKAGE EQUALIZER.

SPECIFICATION forming part of Letters Patent No. 664,928, dated January 1, 1901.

Application filed September 22, 1900. Serial No. 30,812. (No model.)

To all whom it may concern:

Be it known that I, OLIVER COLBORNE, a citizen of the United States of America, and a resident of Chicago, in the county of Cook and State of Illinois, have invented certain new and useful Improvements in Veneer-Package Equalizers, of which the following is a specification.

My invention relates to machines for equalizing and dividing veneer cylinders.

The main objects of my invention are, first, to provide an improved arrangement of supporting-drum and cutting device in machines of this class, and, second, to provide an improved form of collapsible drum.

The further objects of the different parts with which I put my invention into practice will be understood from the following description, with reference to the accompanying drawings, in which—

Figure 1 is a side elevation of a machine constructed according to my invention, being partly broken away. Fig. 2 is a vertical section on the line 2-2 of Fig. 1. Fig. 3 is a vertical longitudinal section of the collapsible drum. Fig. 4 is a longitudinal vertical section of the pulley, sprocket-wheel, shaft, and clutch shown at the lower left-hand part of Fig. 1. Fig. 5 is a reduced perspective view 30 of one of the veneer cylinders for which my machine is designed.

In the device shown the collapsible drum 1 is supported by the hollow shaft 3, which is journaled in the oscillating arms 4 and 5. Said arms 4 and 5 are rigid on the hollow shaft 6, which may be oscillated in the frame by means of the lever 7. Said lever is rigid on the shaft 6. The shaft 6 is journaled in the bearings 8, 9, and 10 of the frame. The sprocket-wheel 11 is mounted on the sleeve 12, which is loose on the shaft 6. The pulley 13 is also loose on the shaft 6 and is normally held free from the sleeve 12 by means of the spring 14. A rod 15 extends through the hollow shaft 6 and has the nuts 16 bearing against the hub of the pulley 13. The rod 15 has the lever 17 pivoted thereto at 18. Said lever is fulcrumed to the frame at 19 and provided with a step 20. The pulley 13 is connected 50 with suitable driving power by means of the belt 21.

The saws 22 are mounted on the shaft 23, which is journaled in the arms 24 of the frame. The mills 25 are likewise mounted on the shaft 26, which is journaled in the arms 27 of the frame. A pulley 28 is rigid on the shaft 23 and serves to drive the saws 22. Said pulley 28 is connected with suitable driving power through the belt 29. A pulley 30 is tight on the shaft 26 and is driven by means of the belt 31, which is also connected with the driving power.

The sprocket-wheel 11 is connected by the chain 32 to the sprocket-wheel 33, which is rigid on the hollow shaft 3 and serves to rotate the collapsible drum 1. The oscillating arms 4 and 5 are connected by means of the rods 34, having thereon the nuts 35. The arm 5 oscillates between the arms 36, which are rigidly secured to the upright 37 of the frame. The arms 36 are connected by a cross-piece 38, which has an aperture therein permitting the rod 39 to pass through the same and into an aperture in the oscillating arm 5. The rod 39 has a shoulder 40 to act upon the spring 41, which normally urges the rod 39 into engagement with the arm 5. A hand-wheel 42 is secured to the free end of said rod 39 and has a cam 43 acting against the cam 44. The cam 44 is rigid on the member 80 45 of the frame. The rod 39 passes through the cam 44. It will be seen that when the hand-wheel 42 is given a half-turn the cams 43 and 44 will coact to withdraw the rod 39 from the oscillating arm 5. Said withdrawal 85 of the rod 39 will permit the drum to be swung toward either side with its oscillating arms 4 and 5 and by means of the lever 7. An adjusting-screw 46 is threaded into each arm 36 and has its inner end projecting toward 90 the oscillating arm 5. The adjusting-screws 46 serve to limit the oscillation of the arm 5.

The hollow shaft 3 of the drum has journaled therein the screw 47, having a right-hand thread at 48 and a left-hand thread at 49. The internally-threaded sleeves 50 are seated on the screw 47. Said sleeves are connected by means of the pins 51 with the external sleeves 52, which are slidingly mounted upon the shaft 3. The pins 51 pass through the slots 53 in the shaft 3. The segments 54 of the drum are connected to the sleeves 52.

by means of the arms 55, which are pivoted to the segments at 56 and to the sleeves at 57. The guide-arms 58 are rigid on the shaft 3 and are grooved for slidingly receiving the arms 59, which are rigid on the segments 54. The screw 47 is provided with shoulders 60 and 61 near the end of the shaft 3. The shaft 3 has a screw 62 seated near said end and extending inwardly between said shoulders 60 and 61. This serves to hold the screw 47 in the proper position longitudinally of the shaft 3. The crank 63 is rigidly secured to the outer end of the screw 47.

Veneer cylinders 65, to equalize which my machine is particularly designed, have the edge of the veneering secured by means of a metal fastening-strip 64.

The operation of my device is as follows: The operator will first turn the crank 63, so as to draw the sleeves 52 toward each other and thus collapse the drum 1. The veneer-cylinder is then placed upon the drum from the right of Fig. 1. The operator will now turn the crank 63 oppositely until the drum 25 has expanded, so as to bear against the inner walls of the veneer cylinder. The operator will now turn the hand-wheel 42, so as to release the arm 5 from the rod 39, and will depress the step 20, so as to cause the pulley 13 to engage with the sleeve 12, and thus rotate the drum through the action of the sprocket-wheels 11 and 33. It will be seen that when the step 20 is depressed the rod 15 will move toward the right of Fig. 1 and will carry the pulley 13 into a clutch engagement with the sleeve 12. The operator will now move the lever 7 toward the rear of Fig. 1 or toward the right of Fig. 2. This will bring the veneer cylinder into contact with the mills 25 and will cause said mills to cut through the metal fastening-strip 64 upon the veneer cylinder 65. (Shown in Fig. 5.) The operator will then move the lever 7 in the opposite direction, and thus bring the veneer cylinder into contact with the saws 22. In the form of drum shown the segments 54 will be made of wood, so as to permit the saws 22 to cut slightly into said segments. It will be seen that the adjusting-screws 46 may be set in proper position to permit the saws 22 to cut entirely through the walls of the veneer cylinder while making but a slight cut into the segments of the drum. The rotation of the drum will cause each cut into the cylinder to extend entirely around same. After said cylinder has been suitably divided or equalized the operator will move the lever 7 to the middle position and will then turn the hand-wheel 42, so as to permit the rod 39 to again engage the oscillating arm 5. He will now turn the crank 63, so as to collapse the drum and permit the removal of the veneer packages or cylinders.

It will be understood that the details of construction of the device shown may be altered in numerous ways without departing

from the spirit of my invention. I therefore do not confine myself to such details except as hereinafter limited in the claims.

What I claim as my invention, and desire to secure by Letters Patent, is—

1. A veneer-package equalizer comprising a supporting-frame; a pair of rotary wood-saws journaled therein on one side of the frame; a pair of rotary metal-cutting mills 75 journaled in said frame on the opposite side; a rotary collapsible drum journaled in the frame between said saws and mills and movable alternately toward each; and means for operating said saws, mills and drum; substantially as described.

2. A veneer-package equalizer comprising a supporting-frame; a pair of rotary wood-saws journaled therein on one side of the frame, a pair of rotary metal-cutting mills 85 journaled in said frame on the opposite side; a rotary collapsible drum journaled in the frame between said saws and mills and movable alternately toward each; means for locking said drum in a position between and free 90 from said saws and mills; and means for operating said saws, mills and drum; substantially as described.

3. A veneer-package equalizer comprising a supporting-frame; a pair of rotary wood-saws journaled therein on one side of the frame, a pair of rotary metal-cutting mills journaled in said frame on the opposite side; a rotary collapsible drum journaled in the frame between said saws and mills and movable alternately toward each; means for locking said drum in a position between and free 100 from said saws and mills; adjustable stops on said frame for limiting said movement of the drum; and means for operating said saws, 105 mills and drum; substantially as described.

4. A veneer-package equalizer comprising a supporting-frame; a pair of rotary cutters journaled thereon; a rotary collapsible drum journaled on said frame and movable toward 110 and from said cutters; said drum comprising a hollow slotted shaft, a pair of interiorly-threaded sleeves longitudinally slidable within said shaft and having right and left hand threads respectively; a series of drum-segments, a series of radial arms pivotally connected to said sleeves and segments, radial guide-arms rigid on said shaft and slidably engaging guide-arms rigid on the segments, 115 and a screw journaled in said shaft and having right and left hand threads adapted to urge said sleeves toward and from each other; an outer connection for turning said screw; and means for rotating said cutters and drum; substantially as described.

5. A veneer-package equalizer comprising a supporting-frame; a series of rotary wood-saws journaled therein toward the upper part 120 of the frame on one side; a series of rotary metal-cutting mills journaled toward the upper part of the frame on the opposite side; a rock-shaft journaled in the lower part of the

frame and having thereon a rigid upwardly-extending arm; a rotary collapsible drum journaled in said arm and movable therewith between said saws and mills alternately toward each; a hand-lever at one end of the frame for rocking said shaft; means at said end of the frame for starting and stopping the rotation of said drum; means at said end of the frame for adjusting the expansion of said

drum; and means for rotating said saws, mills and drum; substantially as described.

Signed at Chicago, Illinois, this 18th day of September, 1900.

OLIVER COLBORNE.
